FIG. 4.

UNITED STATES PATENT OFFICE

2,350,148

THERMOSTAT STRUCTURE

Henry C. Bostwick, Cranford, N. J., assignor to
Westinghouse Electric & Manufacturing Company, a corporation of Pennsylvania

Application December 22, 1942, Serial No. 469,821

4 Claims. (Cl. 209—122)

My invention relates to thermostat structures, and has for an object to provide an improved structure of this kind.

A further object of the invention is to provide an improved thermostat having a snap-acting, laminated metal, heat-responsive device which operates over a relatively wide range of temperatures.

These and other objects are effected by my invention as will be apparent from the following description and claims taken in connection with the accompanying drawing, forming a part of this application, in which:

Fig. 1 is a side view of an electric iron having my improved thermostat applied thereto;

Figs. 2 and 3 are, respectively, top and side elevations of the thermostat shown in Fig. 1; and

Fig. 4 is a diagrammatic view of the switching means forming a part of the thermostat shown in Figs. 2 and 3.

Reference will now be had to the drawing wherein I have shown my improved thermostatic structure, generally indicated at 10, applied to an electric iron, the base plate 11 of which is heated by an electric heating element 12 of any well-understood construction. The base plate 11 is provided with a cover 13 which houses the thermostat 10 and which supports a handle 14. The iron is also provided with a second handle 15 for adjusting the thermostat 10 and, therefore, the temperatures at which the base plate 11 operates, further reference to this adjustment being made hereinafter.

Referring to Figs. 2 and 3, the thermostat 10 includes a supporting base 16, notched as shown at 17, for the reception of mounting screws 18 which are threaded in the base plate 11 of the iron, as shown in Fig. 1. This mounting provides for the transfer of heat between the base plate 11 and the supporting base 16 of the thermostat. The supporting base 16 is provided with an upstanding boss 19 which is threaded inwardly, as shown at 21, to an adjusting stem 22, the upper end of which is connected to the handle 15. The lower end of the adjusting stem 22 is rotatably mounted in an opening 23 formed in the center of a disc 24 which defines the heat-responsive element of the thermostatic structure 10.

The disc 24 which is of laminated metal construction is dished, as shown in Fig. 3, and, when heated, changes its curvature with a snap action, as is well understood. The temperatures at which the disc snaps from one position to the other are adjusted by mechanically stressing the disc. Rotation of the stem 22 clockwise as viewed in Fig. 3 lowers the central portion of the disc 24 and reduces the mechanical stress therein and, therefore, increases the temperature of the disc

at which it snaps to its other position. Conversely, counterclockwise rotation of the stem 22 raises the center of the disc 24 and increases the stress therein so that it operates at reduced temperatures. As this operation is well understood, no further description of the same is deemed necessary. The angular movement of the stem 22 is limited by stops 25 and 26 carried by the boss 19 and engageable with a pin 27 extending radially from the stem 22. Conventional adjustable stops 28 are provided for engaging the disc 24 and limiting the reverse curvature of the disc.

The disc 24 carries a plurality of circumferentially-spaced contacts 29 which, in the closed position of the thermostat, engage a plurality of stationary contacts carried by the base 16 and insulated therefrom. The stationary contacts are best shown in Fig. 4 and are numbered 31 to 35, inclusive. As shown in Fig. 4, the heating element 12 is energized from a source of power indicated by line conductors L₁ and L₂ the former of which is connected to one terminal of the heating element 12 and the latter of which leads to an upstanding terminal 36 connected to the stationary contact 33. The opposite terminal of the heating element 12 is connected to an upstanding terminal 37 forming a part of the contact segment 32.

In order to reduce the temperature differential of the base 11 provided by the thermostat, a small heater 38 is disposed in heat transfer relation with the disc 24. This heater 38 is connected to the stationary contacts 31 and 35 and is energized in series with the main heating element 12 in the closed position of the thermostat 10, as will be apparent from Fig. 4. In the open position of the thermostat, both elements 12 and 38 are deenergized.

The heater 38 is provided for supplementing the heat imparted to the disc 24 by the heated base 11 during energized periods of the heating element 12. This operation is necessary as heat-responsive elements of the disc type having a low operating temperature differential and wide ranges of operating temperatures are difficult to manufacture. For example, a thermostat in an iron, particularly of the steaming type, should be adjustable to maintain mean base temperatures of 350° F. to 550° F., and at base temperature differentials of about 40° F. Disc type heat-responsive elements for this service have been difficult to produce and usually operate at a temperature differential in excess of 100° F.

Accordingly, the heater 38 is employed to supplement the heating provided by the base so that the temperature of the disc 24 is increased one hundred degrees while the base is heated 40° F. The use of a heater of the type shown at 38 has facilitated the manufacture of snap-acting ther-

mostats but difficulty is still experienced in constructing thermostats which provide the relatively high temperatures demanded by steaming irons when ironing cotton goods.

In accordance with my invention, I propose to increase the range of operating temperatures of the base 11 by rendering the heater 38 inactive in the high temperature setting. Accordingly, the heating of the disc 24 at this time is effected only by heat received from the base 11, so that the latter is heated to the cut-off temperature of the disc. The base temperature is, therefore, of the order of 60° F. higher than it would be if the heater 38 were effective. With this operation, the range of temperatures of the base 11 provided by the thermostat is increased by 60° F.

The means for rendering the heater 38 inactive in the high temperature setting of the thermostat includes a resilient switch member 41 electrically connected at 42 to the contact 31 and one terminal of the heater 38. The switch member 41 is engageable with a stationary button 43 electrically connected to the contact 35 and the opposite terminal of the heater 38. When engaging the button 43, the switch member 41 shunts the heater 38 for deenergizing the same. In all positions of the adjusting stem 22 except the high-heat position, the resilient switch member is biased upwardly out of engagement with the button 43. In the high-heat position of the adjusting stem 22, the arm 27 engages a projection 44 carried by the switch member 41 and forces the latter into engagement with the button 43. This position of the apparatus is shown in the drawing. Upon movement of the stem 22 and its arm 27 counterclockwise to any of the lower temperature settings, the bias of the switch member 41 moves the same out of engagement with the button 43 and renders the heater 38 active.

From the foregoing description, it will be apparent that I have effected an increase in the temperature range of a thermostat of the type described by means readily attachable to such thermostats and without necessitating any major changes in the design thereof.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In a thermostat structure for controlling the temperature of a body having electrically energized means for heating the body, the combination of a switch for controlling energization of the electrically energized means, a heat-responsive element disposed in heat transfer relation with the body for actuating the switch, said element being moved to its switch closed and switch open positions in response to respective low and high temperatures thereof; manually operated means for adjusting the heat-responsive means whereby the temperatures to which it responds to operate the switch are varied, an electric heater controlled by said switch and arranged in heat transfer relation with the heat-responsive

element, said heater being energized and deenergized with said electrically energized means, and a second switch operated by the adjusting means for rendering said heater inactive when the adjusting means is moved to the position in which the heat-responsive element responds to maximum temperatures to operate the first-mentioned switch.

2. In a thermostat for controlling the temperature of a body having electrically energized means for heating the body, the combination of a heat-responsive element disposed in heat transfer relation with the body being heated, a switch for controlling energization of said heating means and actuated by the heat-responsive element to closed and open positions in response to respective predetermined low and high temperatures of the heat-responsive element, an electric heater disposed in heat transfer relation with the heat-responsive element and controlled by said switch, means manually movable to a plurality of positions for adjusting said heat-responsive element whereby the temperatures to which the element responds to actuate the switch are varied, and means effective only in the position of the manually movable means, wherein the heat-responsive element responds to maximum temperatures to operate the switch, for rendering said electric heater inactive independently of said switch.

3. In a thermostat for controlling the temperature of a body having electrically energized means for heating the body, the combination of a switch controlling energization of said electrically energized means, a heat-responsive device for closing and opening said switch in response to predetermined low and high temperatures, respectively, means for adjusting said device for varying the temperatures to which it responds to operate the switch, said adjusting means being movable to a high heat position in which the device responds to maximum temperatures for operating the switch, a heater disposed in heat transfer relation with the device and connected in series with said electrically energized means, a second switch shunted across the heater, and means for closing the second switch when the adjusting means is actuated to said high heat position.

4. In a thermostat, a base, a plurality of insulated arcuate contacts carried by the base, a plurality of movable contacts for bridging adjacent ends of a portion of the arcuate contacts, an electric circuit to be controlled connected to a pair of said arcuate contacts, an electric heater connected across a second pair of the arcuate contacts, a heat-responsive laminated metal disc supporting said movable contacts and arranged adjacent said electric heater, means including a rotatable stem for adjusting said disc whereby the temperatures to which it responds to engage and disengage the movable and arcuate contacts are varied, a switch shunted across said second pair of arcuate contacts and said heater and means carried by said stem for closing said switch when the adjusting means is moved to the position wherein the disc operates at maximum temperatures to engage the movable and arcuate contacts.

HENRY C. BOSTWICK.
